CLAIM

The ornamental design for a chain steering wheel cover, substantially as shown and described.

DESCRIPTION

FIG. 1 is a front perspective view of the chain steering wheel cover showing the new design;

FIG. 2 is a front elevation view thereof;

FIG. 3 is a rear elevation view thereof;

FIG. 4 is a left side view thereof;

FIG. 5 is right side view thereof;

FIG. 6 is a top plan view thereof;

FIG. 7 is a bottom plan view thereof; and,

FIG. 8 is a rear perspective view thereof.

The broken lines in the drawings depict portions of the chain steering wheel cover that form no part of the claimed design.

1 Claim, 5 Drawing Sheets
